UNITED STATES PATENT OFFICE

109,884

DESIGN FOR AN ACCORDION

Anonte Bernardi, Aldo Logli, and Mario Zoppi, Detroit, Mich.

Application November 22, 1937, Serial No. 73,107

Term of patent 7 years

To all whom it may concern:

Be it known that we, Anonte Bernardi, Aldo Logli, and Mario Zoppi, citizens of the United States, residing at Detroit, in the county of Wayne and State of Michigan, have invented a new, original, and ornamental Design for an Accordion, of which the following is a specification, reference being had to the accompanying drawing, forming part thereof.

showing our new design.

We claim:

The ornamental design for an accordion, as shown.

ANONTE BERNARDI.
ALDO LOGLI.
MARIO ZOPPI.
